(57) **CLAIM**

The ornamental design for a hat rack, as shown and described.

DESCRIPTION

FIG. 1 is a first perspective view of a first embodiment of a hat rack showing my new design;

FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is a first perspective view of a second embodiment of a hat rack showing my new design;

FIG. 10 is a second perspective view of the second embodiment thereof;

FIG. 11 is a front view of the second embodiment thereof;

FIG. 12 is a back view of the second embodiment thereof;

FIG. 13 is a left side view of the second embodiment thereof;

FIG. 14 is a right side view of the second embodiment thereof;

FIG. 15 is a top view of the second embodiment thereof;

FIG. 16 is a bottom view of the second embodiment thereof;

FIG. 17 is a partial enlarged view of the first embodiment according to the short dash-long dash circle 17 shown in FIG. 1; and,

FIG. 18 is a partial enlarged view of the second embodiment according to the short dash-long dash circle 18 shown in FIG. 9.

The broken lines shown in the drawings depict portions of the hat rack that form no part of the claimed design.

The short dash-long dash lines shown represent the boundaries of the partial enlarged views and form no part of the claimed design.
